UNITED STATES PATENT OFFICE.

EDWARD D. HISCOCK, OF ODELL, OREGON.

CARBURETER-HEATER.

1,378,789.

Specification of Letters Patent.

Patented May 17, 1921.

Application filed June 11, 1920. Serial No. 388,154.

To all whom it may concern:

Be it known that I, EDWARD D. HISCOCK, a citizen of the United States, residing at Odell, in the county of Hood River and 5 State of Oregon, have invented certain new and useful Improvements in a Carbureter-Heater, of which the following is a specification.

This invention relates to internal combustion engines and more particularly to vaporizers for use in connection therewith.

The object of the invention is to provide an attachment for application either to a carbureter or to the intake manifold of a 15 gas engine to facilitate the starting of the explosive engine by supplying a highly explosive heated mixture.

Another object is to provide a simple and efficient attachment of this character to insure the prompt starting of cold gas engines, being constructed so as to provide sufficient heat to supply ample priming fluid to start a heavy engine when cold.

With these and other objects in view, the 25 invention consists in certain novel features of construction as hereinafter shown and described and then specifically pointed out in the claims, and in the drawings illustrative of the preferred embodiment of the 30 invention.

In the accompanying drawings:

Figure 1 represents a perspective view of the attachment constituting this invention.

Fig. 2 is a transverse section thereof.

35 In the embodiment illustrated the attachment comprises a substantially ovate casting 1 having a bore 2 extending longitudinally therethrough and provided at one end with an attaching pipe or coupling 3 while 40 its opposed end is bent upwardly to form a receiving cup 4. The coupling 3 may be of any desired construction and is designed for attachment to the air intake pipe of a carbureter or to be tapped into the intake manifold of a gas engine. The bore extending 45 through the casting is preferably somewhat larger than the discharge openings at the end thereof.

Arranged under and extending laterally 50 beyond opposite sides of the body portion 1 of the attachment is a tray 5 secured to or cast integral with the casting and which is designed to contain gasolene or other inflammable fuel for heating the casting to 55 vaporize fuel to be fed through said casting

to the carbureter or to the manifold as the case may be.

As shown this casting is provided at its top with spaced apertured lugs 7 and 8 to receive a bail 9 for the convenient handling 60 of the device.

It is of course understood that if the device is to be removably attached to the manifold and only used for starting a cold engine it will be necessary to provide a closure for the hole in the manifold which is made to receive the pipe 3. When the device is applied to the carbureter all that is necessary is to insert the gas discharge end 3 in the air intake pipe of said carbureter 70 and hold the device in this position until the engine has been started.

In the use of this attachment the end 3 having been inserted in the manifold opening or the air intake of the carbureter gasolene is placed in the tray 5 and ignited which will thoroughly heat the casting 1. Fuel in the form of gasolene is then introduced through the receiving cup 4 and in its passage through the casting 1 will be 80 thoroughly heated and vaporized before entering the carbureter or manifold. The cranking of the engine will operate to suck into the cylinders this heated vaporized fuel in addition to that supplied by the carbureter thus producing a highly explosive mixture which will insure quick starting of the engine even in extremely cold weather.

The preferred embodiment of the invention is disclosed in the drawings and set 90 forth in the specification, but it will be understood that any modifications within the scope of the claims may be made in the construction without departing from the principle of the invention or sacrificing any 95 of its advantages.

What I claim is:

1. An attachment of the class described comprising a hollow body having a discharge terminal at one end and an upturned receiving cup at its other end, and fuel containing means carried by said body and positioned to direct the heat issuing therefrom around said body.

2. An attachment of the class described comprising a hollow body having a discharge pipe at one end for connection with the air intake of a carbureter or with the manifold of an engine and equipped at its other end with an upturned receiving cup,

said body having at its opposite sides near the bottom thereof a laterally extended fuel containing tray.

3. A device of the class described comprising a hollow body having an intake at one end and a discharge at the other, a fuel container carried thereby adjacent the bot-

tom thereof, and a handle connected with the top for convenient manipulation of the device.

10

In testimony whereof, I affix my signature hereto.

EDWARD D. HISCOCK.
